AUTOMATIC LOCKING JACK

Jean Mercier, Neuilly-sur-Seine, France

Application August 30, 1939, Serial No. 292,639
In France January 18, 1939

10 Claims. (Cl. 121—40)

The present invention relates to hydraulic jacks.

The object of the invention is to provide a jack of this type with safety means for automatically locking the parts, that is to say, preventing the discharge of the motive fluid, as long as the external force to be resisted by the jack exceeds a given value.

Preferred embodiments of the present invention will be hereinafter described, with reference to the accompanying drawings given merely by way of example, and in which:

Fig. 1 is a longitudinal section of a jack, according to the present invention, as used for controlling a retractable landing gear;

Fig. 2 is a diagrammatic view of a jack adapted to resist extension forces;

Fig. 3 is a view similar to Fig. 2 showing another embodiment;

Fig. 4 is a similar view showing a modification.

In the embodiment shown by Fig. 1, the jack includes a cylindrical body 1 and a piston 2 movable therein.

In the embodiment of Fig. 1, the jack is supposed to control the operation of a retractable landing gear including a leg L carrying a wheel R and pivoted to wing W. In order to be able to produce the pivoting of leg L with respect to wing W, the rod 2b of piston 2 is pivoted, at its end 2a to said leg L, while a sliding member 3 carried by cylinder 1 is pivoted at 3a to wing W. Both pivots, preferably, include a certain amount of play. Thus, as long as wheel R is resting on the ground, the weight of the aircraft tends to retract jack 1—2.

Member 3 forms a slide-valve movable in a chamber formed in the head 4 of cylinder 1, said chamber being separated from said cylinder by the end wall 5 thereof. Slide valve 3 consists of a piston having three parts, 3b, 3c, 3d, of different diameters. Part 3b is provided in its periphery with an annular groove 6 adapted to connect the portions 7 and 8 of a conduit 9 which serves to supply or discharge fluid under pressure to or from said jack. Conduit 9 leads, in the embodiment shown in Fig. 1, into cylinder 1, at a point 11 located between piston 2 and end wall 5.

Preferably, there is provided a conduit 10 which branches off from conduit 9 and also opens into cylinder 1 near the end 5 thereof. A check-valve 12 is mounted on this by-pass 10, and this permits of feeding fluid under pressure to the jack, when slide valve 3 closes conduit 9, but prevents the discharge of fluid from the cylinder.

The displacements of slide-valve 3 are limited

in both directions by a shoulder 4a of body 4 and a nut 13 screwed to the open end of this body through which passes a rod rigid with slide-valve 3 and projecting to the outside; these parts 4a and 13 being adapted to cooperate alternately with the larger diameter of portion 3d of piston 3.

Preferably, a certain play is provided in the bore of the nut 13 through which portion 3c of part 3 passes. There is also provided a small radial channel 14 in body 4 in the immediate vicinity of end 5 of cylinder 1. This play and this channel permit the outflow of any fluid which may have been forced into the bore of hollow body 4 as a result of the displacements of part 3, and, thus, the movements of this part will not be impeded by a possible compression of such fluid. A conduit 15 opening into cylinder 1 in the vicinity of the end thereof, through which passes the rod of piston 2, serves, both, to supply a fluid under pressure to cylinder 1 in order to retract the jack, and to evacuate this fluid when fluid is being fed to the other side of the piston in order to expand the jack.

This jack works in the following manner: when the landing gear is retracted, the jack is also retracted and piston 2 is near the end wall 5 of the cylinder. The fluid force entering through port 15 also forces cylinder 1 away from the pivot point 3a, which in turn forces collar 3d against nut 13, also the spring 17 holds groove 6 opposite portions 7 and 8 of pipe 9, which corresponds to collar 3d bearing against nut 13.

When the landing gear is to be lowered, a fluid under pressure is fed through pipe 9, so that the jack expands, that is to say piston 2 is pushed outwardly.

The expansion of the jack does not meet any substantial resistance, so that the force acting on the end wall 5 does not effect the slide-valve 3 which remains in the same position to connect portions 7 and 8 of pipe 9 with each other. The landing gear is, thus, lowered and brought into the position shown by Fig. 1. In the event there was substantial resistance to the lowering of the landing gear, the fluid force entering through port 9 would force the end wall 5 to close the portions 7 and 8 against the effect of spring 17.

When the airplane has landed, a portion of its weight pushes sliding member 3 inwardly with respect to chamber 4, against the action of spring 17. The connection between portions 7 and 8 of pipe 9 is, then, cut off. Under these conditions, fluid can no longer be discharged from the jack since it cannot escape through branch pipe 10, in

view of the presence of check valve 12, while the flow through 7-8 is cut off by the displacement of slide-valve 3. Therefore, while the action of the airplane weight on the jack tends to produce a discharge of fluid from the body of said jack, this action also displaces slide-valve 3 in such manner as to prevent said discharge.

As long as this weight is acting, that is to say, as long as the airplane is bearing on the ground, the jack cannot be retracted. On the contrary, as soon as the airplane has taken off, the air lift removes the weight on the landing gear and thus member 3 is no longer forced inwardly by the weight of the airplane. Due to the play provided in pivots 2a, 3a and in the absence of any load, spring 17 displaces member 3 outwardly. The jack can, then, be retracted by feeding fluid under pressure through conduit 15, since the fluid on the right hand side of piston 2 can escape through pipe 9, the portion 7 and 8 of which are now connected together through groove 6.

The jack shown by Fig. 2 is exactly similar to that of Fig. 1, with the difference that it is adapted to operate by retracting, against the action of an external force F'. The fluid under pressure is admitted through pipe 9 so as to move piston 2 inwardly with respect to body 1, since pipe 9 opens at 21, on the right hand side of said piston (while in Fig. 1 it opened at 11, at the left hand side of said piston). Pipe 20, with its check valve 22, plays the same part as pipe 10, with its check valve 12. Nut 23 plays the same part as nut 13 of Fig. 1. Spring 27 plays the same part as spring 17 of Fig. 1, tending to hold slide-valve 3 in the position connecting together the portions 7 and 8 of pipe 9. The fluid force entering through port 21 tends to force the cylinder 1 in the direction of the arrows F' acting against the force of spring 27. If the force becomes excessive, it will close the portions 7 and 8, while the force is still applied through the check valve 22 to the cylinder.

In the embodiment of Fig. 3 slide-valve 3 is subjected, both, to the action of an external force F' and to the action of the fluid contained in the jack. The jack is similar to that shown in Figs. 1 and 2, with the exception that the bore formed in head 4 opens into cylinder 1. Piston 3 is provided with two stops 38 and 39 which limit its displacements with respect to head 4, and its diameter is considerably smaller than that of piston 2. A compensating spring 37 may be placed between stop 39 and head 4. A conduit 35 opens at 59 into head 4 and a branch 30 provided with a check valve 32 opens at 51 into cylinder 1. Another conduit 9 extends across head 4 and opens at 31 into cylinder 1 below the lower face of piston 2. According to whether it is desired to extend or to retract the jack, fluid under pressure is supplied through conduit 35 or through conduit 9, and is discharged through conduit 9 or through conduit 35, respectively. Piston 3 is provided with a bent conduit 52 extending from a point 53 on its cylindrical wall to its inner end, so as to connect conduit 35 with the inside of cylinder 1 when stop 38 is in contact with head 4. A groove 6 provided in piston 3 connects portions 7 and 8 of conduit 9 together when piston 3 is in this position. The fluid force entering from conduit 35 tends to work against this spring 37 to close member 3, but the fluid enters through 51, when fluid enters port 31 it tends to displace cylinder 1 in such a direction as to assist spring 37.

The jack, according to Fig. 3 will work as follows:

It will be supposed that the parts are in the position shown by Fig. 3 (the external force F' against which the jack is to act opposing inward displacement of piston 3, while piston 2 rests on a stationary part, for instance, the ground).

In order to extend the jack, fluid under pressure is supplied through conduit 35. This fluid passes through 30, lifts valve 32 and enters cylinder 1 at 51. When the pressure reaches a certain value in cylinder 1, as piston 2 cannot move in said cylinder in view of discharge 9 being cut off at 7, piston 3 is driven outwardly. When stop 38 of piston 3 has come into contact with head 4, the fluid under pressure in conduit 35 can also flow through 53 and 52 into cylinder 1; groove 6 affords communication between portions 7 and 8 of conduit 9, so that the fluid contained in cylinder 1 below piston 2 can be discharged through orifice 31 and conduits 9. Accordingly, the jack is extended.

If, at any time, the pressure drops in conduit 35 while an external force, acting simultaneously in the direction of arrows F and F', tends to force both pistons 2 and 3 into cylinder 1, then, piston 3 will move quicker inwardly with respect to said cylinder because its inward movement requires the expulsion of a much smaller amount of fluid than that of piston 2.

Immediately upon moving inwardly piston 3 cuts off the flow of fluid through conduits 52 and 9, and the jack is locked in the position it occupies, since the fluid entrapped between head 4 and piston 2 cannot escape, as check valve 32 cuts off conduit 30.

In order to retract the jack, fluid under pressure is supplied through conduit 9. Since the fluid force enters by conduit 9, the discharge on the other side of the cylinder must be through 53 and out conduit 35, while conduit 35 is connected to the discharge. This forces cylinder 1 in an opposite direction to the arrow F' and assists spring 37 to position the member 3 so that fluid may be discharged. This movement of 3 and discharge is possible only if piston 3 is in the position in which stop 38 is applied against head 4. If a sufficient downward force (such, for instance, as a weight of an airplane) is exerted on piston 3, so that said piston is pushed back into the jack, the retraction of the jack is impossible. A spring 37 may be provided in order to keep piston 3 in the position in which the jack can be retracted except when the forces F, F' exceed a given value.

An auxiliary conduit 55 including a check valve 56 may be provided to permit the discharge of the small amount of fluid which must be evacuated from cylinder 1 to allow piston 3 to enter the same without appreciable variation of pressure. While fluid pressure remains at port 31, there cannot be any discharge of fluid back through the line 9, or check valve 56, or line 55.

When the device, according to Fig. 3, is used in connection with a retractable undercarriage, for instance, in the manner shown in Fig. 1, then, the head of auxiliary piston 3 must be so dimensioned, taking into account the surface area of piston 2, that piston 3 cannot be displaced from the locking position as long as the external force (weight of the airplane) exceeds a predetermined value.

When so used piston 3 will lock the jack, practically, until the wheels of the undercarriage have left the ground, and this structure, accord-

ingly, prevents a premature raising of the undercarriage even in the event of an erroneous operation of the controls by the pilot.

Fig. 4 shows a jack, according to the present invention, in which the distributing means 3, consisting, for instance, of an auxiliary piston is subjected, both, to the pressure of the fluid contained in the cylinder, and to the external forces illustrated by arrows F and F' which tend to pull the jack into an extended position.

In this embodiment auxiliary piston 3 extends across the end 4 of cylinder 1 in which it is axially slideable. The head 43 of piston 3 in cylinder 1 has a diameter practically equal to that of the head of piston 2. Portions 7 and 8 of conduit 9 15 can be interconnected by annular groove 6 formed in the rod of piston 3. Preferably, a reaction spring 47 is interposed between the head 43 or part 3 and piston end 4. This spring urges part 3 toward its unlocking position, i. e., that in which groove 6 interconnects portions 7 and 8 of conduit 9. In this position the fluid force entering port 41 tends to displace the cylinder 1 away from the pivot connection of member 3 thus closing the line 7-8, but the line 40 permits fluid pressure to pass check valve 42 and pass to port 41.

Conduit 9 is connected with a branch conduit 40, provided with a check valve 42, which permits of feeding fluid under pressure to port 41 where conduit 9 opens into cylinder 1 for retracting the jack against the action of forces F, F'. But fluid cannot be discharged through by-pass 40. The conduit which serves for the supply of fluid under pressure to the jack, when it is desired to extend, the same, preferably, opens into cylinder 1 at 45, between head 4 thereof and head 43 of piston 3. The fluid force entering port 45 will tend to force head 3 toward F' and force the cylinder 1 toward F thus assisting the spring 47.

Head 43 of piston 3 is, preferably, mounted in cylinder 1 with a certain amount of play so that fluid can flow with a suitable resistance, from one side to the other of said piston head 43 to the surface of piston 2. The restricted space left between piston head 43 and cylinder 1, and the strength of spring 47 should be carefully selected so as to insure the piston 3 being forced away from a locking position to prevent any risk of piston 3 coming back to the locking position while the jack is being extended as the exhaust fluid must pass through the conduits 7, 8 and 9. Piston 3 might be returned to the locking position under the force of the fluid admitted into the space between pistons 2 and 3 through conduit 45, thus preventing the escape of the exhaust fluid, but by providing a restrictor around the head 43, the fluid entering through 45 will build up against the restricted head forcing it toward F'. When sufficient fluid has passed, the restricted head, it will force the piston 2 to an extended position.

The foregoing description is not intended to limit the present invention which extends to all changes, modifications, and equivalents within the scope of the appended claims.

Having now described my invention, what I claim as new and desire to secure by Letters Patent is:

1. A hydraulic jack for use between two parts to produce relative displacement thereof, which comprises, in combination, liquid feed means and discharge means for said jack, and means, subjected to forces acting between one of said parts

and the jack, for cutting off said discharge means when an external force transmitted by at least one of said parts tends to deform the jack in the direction opposed to that in which the liquid under pressure therein tends to operate.

5 2. A hydraulic jack for use between two parts to produce relative displacement thereof, which comprises, in combination, liquid feed means and discharge means for said jack, means, subjected to forces acting between one of said parts and the jack, for cutting off said discharge means when an external force transmitted by at least one of said parts tends to deform the jack in the direction opposed to that in which the liquid under pressure therein tends to operate, and elastic means for urging said last mentioned means in the position thereof corresponding to the open position of said discharge means.

10 3. A hydraulic jack for use between two parts to produce relative displacement thereof against an external force, which comprises, in combination, two elements slideable with respect to each other, by hydraulic pressure, liquid feed means and discharge means for said jack and valve means, movably carried by one of said elements, subjected to forces acting between one of said parts and the jack, for controlling said discharge means, adapted to produce the closing thereof when an external force transmitted by at least one of said parts tends to deform the jack in the direction opposed to that in which the liquid under pressure therein tends to operate.

15 4. A hydraulic jack for use between two parts to produce relative displacement thereof against an external force, which comprises, in combination, two elements slideable with respect to each other, by hydraulic pressure, liquid feed means and discharge means for said jack, valve means, movably carried by one of said elements, subjected to forces acting between one of said parts and the jack, for controlling said discharge means, adapted to produce the closing thereof when an external force transmitted by at least one of said parts tends to deform the jack in the direction opposed to that in which the liquid under pressure therein tends to operate, and spring means interposed between said valve means and the jack element by which it is carried, for urging said valve means toward the position thereof of corresponding to the open position of said discharge means.

20 5. A hydraulic jack for use between two parts to produce relative displacement thereof, which comprises, in combination, liquid feed means and discharge means for said jack, and means, subjected both to forces acting between one of said parts and the jack, and to the pressure of the liquid in said jack, for cutting off said discharge means when an external force transmitted by at least one of said parts tends to deform the jack in the direction opposed to that in which the liquid under pressure therein tends to operate.

25 6. A hydraulic jack for use between two parts to produce relative displacement thereof which comprises, in combination two elements movable with respect to each other, to wit a cylinder and a piston movable therein, means for feeding a liquid under pressure into said jack on one side of said piston, a conduit opening into said cylinder on the same side of said piston, for the discharge of said liquid from said cylinder, and a slide valve carried by one of said elements so as to be movable with respect thereto in the axial direction of said piston and said cylinder, subjected to forces acting between one of said parts

and the jack, said slide valve being adapted to cut off said conduit when an external force transmitted by at least one of said parts tends to deform the jack in the direction opposed to that in which the liquid under pressure therein tends to operate.

7. A hydraulic jack for use between two parts to produce relative displacements thereof which comprises, in combination, two elements movable with respect to each other, to wit a cylinder and a piston movable therein, means for feeding a liquid under pressure into said cylinder on one side of said piston, said means including a feed conduit and a check valve in said conduit adapted to permit only the flow of liquid therethrough toward said cylinder, a discharge conduit starting from the cylinder, on the same side of said piston as said first mentioned conduit, and a slide valve carried by one of said elements so as to be movable with respect thereto in the axial direction of said piston and said cylinder, subjected to forces acting between one of said parts and the jack and said jack, said slide valve being adapted to cut off said second mentioned conduit when an external force transmitted by at least one of said parts tends to deform the jack in the direction opposed to that in which the liquid under pressure therein tends to operate.

8. A combination according to claim 7 including elastic means for yieldingly opposing the displacement of said slide valve produced by the effect of said external force transmitted by at least one of said parts.

9. A hydraulic jack for use between two parts to produce relative displacement thereof, which comprises, in combination, two elements movable with respect to each other, to wit, a cylinder and a piston movable therein, means for feeding a

liquid under pressure into said jack on one side of said piston, a conduit opening into said cylinder on the same side of said piston, for the discharge of said liquid from said cylinder, and a slide valve carried by one of said elements so as to be movable with respect thereto in the axial direction of said piston and said cylinder, subjected to forces acting between one of said parts and the jack, said slide valve forming a piston 10 extending into said cylinder so as to be also subjected to the action of the liquid pressure in said cylinder, said slide valve being adapted to cut off said conduit when an external force transmitted by at least one of said parts tends to deform the 15 jack in the direction opposed to that in which the liquid under pressure therein tends to operate.

10. A hydraulic jack for use between two parts to produce relative displacement thereof, which comprises, in combination, two elements movable with respect to each other, to wit, a cylinder and a main piston movable therein, means for feeding a liquid under pressure into said jack on one side of said piston, a conduit opening into said cylinder on the same side of said piston, for the discharge of said liquid from said cylinder, and a slide valve carried by one of said elements so 20 as to be movable with respect thereto in the axial direction of said piston and said cylinder, subjected to forces acting between one of said parts and the jack, said slide valve forming a piston 25 extending into said cylinder and of a cross section smaller than that of said main piston and being subjected to the action of the liquid pressure in said cylinder, said slide valve being adapted to cut off said conduit when an external force transmitted by at least one of said parts tends to oppose the action of the jack thereon.

JEAN MERCIER.
